UNITED STATES PATENT OFFICE

CHARLES P. PROFFATT, OF LOS ANGELES, CALIFORNIA, ASSIGNOR OF ONE-THIRD TO SAMUEL F. MOULTON AND ONE-THIRD TO JOHN C. MOULTON, BOTH OF LOS ANGELES, CALIFORNIA

ILLUMINATED FOUNTAIN

Application filed September 4, 1929. Serial No. 390,298.

This invention relates to illuminated fountains and has for an object the provision of novel means whereby water emanating from a fountain may be given the effect of a colored waterfall or geyser, the said invention including means for illuminating a column of water or a spray thereof.

It is a further object of this invention to provide means for controlling the flow of water and to disperse or separate or spread the water, according to the effect desired.

It is furthermore an object to produce a fountain of novel construction having illuminating means by which the water is lighted.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in elevation of a fountain showing a single column;

Figure 2 illustrates a sectional view of illuminating means associated with the water distributing means;

Figure 3 illustrates a top plan view of the device shown in Fig. 2;

Figure 4 illustrates a sectional view of an illuminating fountain embodying a different construction;

Figure 5 illustrates a top plan view thereof;

Figure 6 illustrates a fountain having another construction;

Figure 7 illustrates a sectional view of a fragment of a fountain showing the diaphragm or water discharge instrumentality;

Figure 8 illustrates a plan view of a sectional transparent plate;

Figure 9 illustrates the arrangement of a bypass for regulating the pressure of water; and

Figure 10 illustrates a sectional view of a conventionally shown fountain with illuminating means for concentrating the rays of light with respect to the stream.

The inventor does not wish to be limited with respect to the external configuration of the bowl of the fountain, its pedestal, or the like, but it is conventionally shown and identified by the numeral 10 in Figure 1. The nozzle 11 is shown above the bowl and it may comprise one of the types disclosed herein.

In Figures 2 and 3, the water distributing and illuminating instrumentalities are shown detached from the bowl of the fountain or other parts thereof, and it is to be understood that one such apparatus may be installed in association with any suitable fountain.

In the embodiment of the invention shown in Figure 2, a lamp casing or closure 12 will, of course, be provided with the usual lighting fixtures, such as sockets, or the like, which need not be described in detail, as they may be employed or selected to suit particular requirements.

An electric lamp 13 is conventionally shown below a colored glass plate 14, which may be employed in association with a gasket or gaskets, such as 15, above and below the glass plate, although, obviously, one or more gaskets may be employed and the thickness thereof may be changed to suit conditions. The lamp casing has a light reflective inner surface.

The device of Figure 2 embodies an inner casing or housing 16 whose wall 17 tapers upwardly and terminates in a nozzle 18 and there is an outer casing 19 in spaced relation thereto whose wall is approximately parallel to that of the wall 17. The casings 16 and 19 each has a cylindrical lower portion, and the outer casing is connected at its upper end with the member 17 effective to close the upper end of the casing 19. The wall 17 has a plurality of apertures 20 through which water escapes from the passage between the walls 17 and 19 and water is supplied to the interior of the device. A service pipe 21 extends to the interior of the casing or housing 19.

When the lamp is illuminated, the light will, of course, show through the colored glass, which color may be unitary throughout the glass or it may be variegated, as those skilled in the art will understand.

The mechanical features entering into the assembly of the parts are immaterial and may be changed to suit particular requirements, but the ordinary flanges 22 and 23 are shown, 5 being secured together by fastenings 24, such as bolts or the like, and, of course, suitable gaskets may be employed where they are required for effecting watertight joints.

The parabolic reflector will concentrate 10 the light rays and the water being in an agitated condition will be centered at the discharge orifice and the rays striking the discharge will illuminate the same.

In that form of the invention illustrated 15 in Figure 4, a casing 25 similar to the reflector 12 is employed with the lamp installed, but in this form a tank 27 has a glass closure 26 at its bottom through which the light is visible. In this form of the invention, a 20 concave plate 28 is employed and it may be provided with a plurality of apertures, such as 29, of different sizes through which water will be ejected by a pressure that will lift the water to a predetermined height and 25 the water, of course, will be colored in accordance with the color of the glass employed in the bottom of the tank. A baffle plate 30 is held by a screw 31 threaded in the wall of the tank so that the baffle plate may be 30 adjusted to different distances with respect to the supply pipe 32 which delivers water to the tank. The employment of the baffle plate insures that the pressure of the water through the different apertures will be uniform 35 and will prevent undue swirling of the water within the tank.

In Figure 6, a casing 33 similar to the other casings employed is associated with the lamp, but in this construction the superimposed 40 water conduit 34 tapers upwardly and terminates in a nozzle 35. A colored glass plate 36 is interposed between the lamp and this water conduit so that the column of water emanating from the nozzle is appropriately 45 colored. In this form of the invention, water is prevented from swirling in its passage upwardly in the conduit through the employment of a plurality of radially disposed fins 35a whose edges engage the inner wall of the 50 conduit and they project outwardly into the conduit a suitable distance. In this form of the invention, obviously any appropriate arrangement of the packing or gaskets may be employed and the inventor does not wish to 55 be limited with respect to them.

Figure 7 shows a slightly modified form of plate corresponding to the plate 28, except that it is straight and it is identified by the numeral 37. This is to be associated 60 with a tank 38 and suitable fittings 39 may be employed in connection therewith. Only fragments of these parts are shown in Figure 7, but enough is illustrated to enable one skilled in the art to understand the same. Instead of having the plate 28 concave, as

shown in Fig. 4, or flat, as shown in Fig. 7, it may obviously be convexedly shaped.

In order to regulate the dispersion of the water within any of the tanks, the plate of the deflector 41 is provided with bypass openings or holes 40 through which water may escape. These holes are controlled, that is to say, they are closed or partially closed through the employment of a segmental plate 41 conforming to the contour of the inner wall of the plate, the said plate having projections 42 which fit into and close the holes. The projections may be tapered in order that the control of the holes may be regulated to increase or diminish the capacity of the bypass. A suitable screw 43 may be swiveled in the plate and threaded in an opening 44 of the tank with the parts in operative relation to permit the projections to enter the bypass holes.

Figure 8 illustrates the employment of a transparent element for the bottom of the water holder or tank comprising a plurality of sections 45 differently colored and through which light may be projected to produce a variegated coloring of water issuing from the fountain. The sections of the colored material are bound together by a resilient ring 46 so that they will be held in place when assembled with relation to the reflector and the tank.

In illuminated fountains the focusing of the light rays with respect to the spray or stream is essential, but, as this is well known in the art, it is believed unnecessary to refer to it except in a general way.

The inner surfaces of the elements 12, 25 and 33 will be reflective and of parabolic form, or light ray concentrating or directing instrumentalities may be employed, or, when lenses are used, the reflector may be globular as conventionally shown in Fig. 10. The manner of converging or diverging rays of light through the employment of lenses is well known and they will be employed in the device of this invention in accordance with the requirement. In Figure 10, the water circulating receptacle 45' may be of the general type illustrated in Fig. 6 with a nozzle 46' and a water delivery pipe 47. A colored plate 48 may be located above the lamp 49 and suitable lenses 50 and 51 in a suitable manner below the water so that the rays of light from the lamp will be focused through the nozzle.

Where spray type units are employed, better illuminating results are usually obtained by focusing so that when the spray is on the outside the focus will be on the outside, but when the spray is on the inside the light will be focused to the inside. Also, where the spray is in the center, the focus of light should be to the center.

While, as stated, a focusing device such as is shown in Fig. 10 may be employed, a satis-

factory result may also be obtained by shaping the reflectors 12, 25 and 33 and locating the lamp in such relation thereto that proper lighting effects will result, as the light rays will be concentrated at the nozzle, beyond which they are diffused, striking upon the spray and deflected atoms of water.

I claim:

1. In an illuminated fountain, the combination of a lamp supporting socket and lamp mounted therein, a reflector supported on said socket and forming a supporting base, a water chamber on said base having a restricted outlet, a cover plate pervious to light interposed between said reflector and chamber, a water supply pipe connected to said chamber adjacent the bottom thereof, and baffle means in said casing between the water inlet and outlet.
2. In an illuminated fountain, the combination of a lamp supporting socket and lamp mounted therein, a reflector supported on said socket and forming a supporting base, a water chamber on said base having a restricted outlet, a cover plate pervious to light interposed between said reflector and chamber, a water supply pipe connected to said chamber at right angles to its outlet and adjacent the bottom thereof, and an inverted perforate cone shape baffle in said casing between the water inlet and outlet.
3. In an illuminated fountain, the combination of a lamp supporting socket and lamp mounted therein, a reflector supported on said socket and forming a supporting base, a water chamber on said base having a restricted outlet, a cover plate pervious to light interposed between said reflector and chamber, a water supply pipe connected to said chamber at right angles to its outlet and adjacent the bottom thereof, and a combined adjustable baffle and control valve member in said casing between the water inlet and outlet.
4. In an illuminated fountain, the combination of a lamp supporting socket and lamp mounted therein, a reflector supported on said socket and forming a supporting base, a water chamber on said base having a restricted outlet, a cover plate pervious to light interposed between said reflector and chamber, a water supply pipe connected to said chamber at right angles to its outlet and adjacent the bottom thereof, and a series of radial spaced longitudinally extending baffle plates in said casing between the water inlet and outlet.

CHARLES P. PROFFATT.
